(57) **CLAIM**

The ornamental design for a ripstop windcheater jacket, as shown and described.

DESCRIPTION

FIG. 1 is a front perspective view of a jacket with the zipper fully unzipped according to a first embodiment of my new design;

FIG. 2 is a front perspective view shown in FIG. 1 with the zipper partially unzipped;

FIG. 3 is a front perspective view shown in FIG. 1 with the zipper fully zipped;

FIG. 4 is a back perspective view of the jacket shown in FIG. 1;

FIG. 5 is a left side perspective view of the jacket shown in FIG. 1;

FIG. 6 is a right side perspective view of the jacket shown in FIG. 1; and,

FIG. 7 is a perspective view of a person wearing the jacket shown in FIG. 1.

The broken line showing of a person is included for the purpose of illustrating environmental structure and forms no part of the claimed design.
